COLUMN SELECTING MEANS FOR CARD-SORTING MACHINES

Karl J. Braun, Glenbrook, Conn., assignor to
Control Instrument Company, Inc., Brooklyn,
N. Y., a corporation of New York

Original application November 25, 1944, Serial No.
565,108, now Patent No. 2,454,628, dated No-
vember 23, 1948. Divided and this application
October 16, 1948, Serial No. 54,986

9 Claims. (Cl. 235—61.11)

1

This invention relates to improvements in statistical card sorting means and has particular reference to a column selecting mechanism for the sensing device of the machine, this application being a division of my copending application, Serial No. 565,108, filed November 25, 1944, now Patent No. 2,454,628, dated November 23, 1948.

An object of the present invention is to provide an improved mechanism of simple and practical construction which will enable the columnar adjustment of a card sensing device without interference with other associated parts of the machine.

The inventive idea involved is capable of receiving a variety of mechanical expressions one of which, for purposes of illustration, is shown in the accompanying drawing; but it is to be expressly understood that said drawing is employed merely for the purpose of facilitating the description of the invention as a whole and not to define the limits thereof, reference being had to the appended claims for this purpose.

In the drawing:

Fig. 1 is a fragmentary longitudinal sectional view of a card sorting machine constructed in accordance with the invention, and

Fig. 2 is a fragmentary isometric view of the sensing device and the columnar adjusting mechanism therefor.

The drawing illustrates only those portions of a sorting machine sufficient for an understanding of the general operation thereof and of the invention herein involved, and reference is made to the above identified patent for a description of the complete machine.

As shown in Fig. 1, cards are stacked in the magazine 30 and fed therefrom in a well known manner by a picker device 96 which is reciprocated through the medium of the linkage generally indicated at 99. As a card is fed from the magazine, it passes between feed rollers 62 to a continuously rotatable sensing device 33 in the form of a wheel which analyzes each card while in transit beneath the device. From the sensing position, the cards pass between rollers 64 and are picked up by the endless conveyor 55 for deposit into the various horizontally arranged pockets 34 in accordance with their analysis by the sensing device.

Said device comprises groups of sensing pins 105, with each group also including a detector pin 106 utilized to sense the presence or absence of a card at the sensing position to thereby control a distributing mechanism fully explained in

2

said patent. Briefly, said distributing mechanism is controlled by a detector slide 107 and the selector slides 108 rotatable with the wheel 33 and all having notches 112 in their outer edges and all normally urged to the left, as viewed in Fig. 2 by springs 113, but being prevented from doing so, until a sensing position of a slide is reached, by means not shown in this application. Should a detector pin 106 fail to engage the leading edge portion of a card at the sensing position of said pin, the latter will not enter a notch 112 in the associated slide 107 also at said position, and said slide will then be moved by its spring 113 to align the recess 116 in the slide with all the recesses in the slides 108 of the group in which said slide 107 is contained, whereupon a locking bail 117 normally resting upon the inner edge of the slide 107 will enter said recesses 115, 116 to lock said slides, with the result that said distributor mechanism will be unaffected by any subsequent sensing of a hole in the improperly fed card which caused the operation of the detector slide. With a card in proper position for sensing, the detector pin 106 will contact the card and enter a notch in the slide 107 to lock the same and any pin 105 entering a hole in said card will not engage in a notch 112 in the associated slide 108 and the latter will consequently be moved by its spring 113 to control the mentioned distributor mechanism so that said card will be deposited into its proper pocket.

The columnar adjustment of the sensing wheel 33 and associated operations, as shown in Fig. 2, will now be described. It is understood that said adjustment is effected before starting a sorting operation and is for the purpose of positioning the sensing wheel along the shaft 37 (Fig. 1) so that the sensing pins will rotate in a plane directly above predetermined columns of cards to be analyzed. Said adjustment is accomplished by means of a feed screw 121 rotatably mounted in machine side plates (not shown) and carrying a follower block 122 having rollers 123 engageable on opposite sides of the sensing wheel. Said block contacts the front wall 124 (Fig. 1) of the magazine 30 so that as the screw 121 is rotated in either direction the block will move therewith and thus shift the wheel axially and with respect to the columns of a card. The thread pitch of the shaft 121 is such that one complete revolution thereof by the crank 32 will shift the block 122, and consequently the wheel 33, a distance equal to the space between two adjacent columns of a card. An apertured indicator 125 carried by the block 122 moves over an

index scale 126 to indicate the position of the sensing wheel with respect to the card columns. In order that the turning of the shaft 121 may be terminated at the conclusion of a complete revolution and the sensing wheel accurately positioned relative to the desired card column, said shaft carries a cam roller 127 having a transverse groove 128 in its periphery in which a roller 129 engages when the sensing wheel is correctly set relative to a card column. Said roller 129 is carried by one end of a rocker arm 130 the other end of which is joined to a rocker shaft 131 by means of the link 132 and arm 133. A coil spring 134 exerts a constant downward pull upon the arms 133 and 130 so that the roller 129 will be maintained in contact with the periphery of the roller 127 and the groove 128 therein and said downward pull is just sufficient to normally maintain the vertically movable card supporting plate 135 in its upper position where it cooperates with the sensing pins 105-106.

Said plate 135 is mounted at the sensing position in cooperation with the sensing wheel 33 and, during sorting, is in its upper position so as to maintain the cards passing thereover in operative association with the sensing pins, the upward movement of the plate being limited by engagement of the roller 129 in the groove 128. For the purpose of permitting any pin which encounters a hole in a card to pass completely therethrough and thus not be forced inwardly toward its locking engagement with one of the slides 107, 108 by contact with said plate 135, the upper surface of the latter is provided with a plurality of channels 136 extending in the direction of movement of the cards for receiving the outer ends of said pins in any columnar position of the sensing wheel. Therefore, in order to prevent possible mutilation of the pins when axially adjusting the wheel 33, means are provided for lowering said plate 135 sufficiently to permit said pins to freely pass laterally thereover without contacting the side walls of any channel 136. To this end, the plate 135 is supported by a bracket 137 linked to the rocker arms 138 fixed upon the rocker shaft 131. With this arrangement, as the crank 32 is initially turned to effect an adjustment of the wheel 33, the cam roller 127 will depress the roller 129 as the latter is disengaged from the groove 128, and the arm 130 is thus moved about its pivot to rock the shaft 131 in the proper direction to depress the plate 135. With the roller 129 engaging the high surface of the cam roller 127, the plate 135 will be held in its lowered position free of the sensing pins on the wheel 33 until a complete revolution of the shaft 121 and consequent shifting of said wheel the distance between two adjacent columns is effected, whereupon said roller 129 again enters the groove 128 under the influence of the spring 134, and the rocker arm 130 then reverses its movement to raise the plate 135 to its operative position in which the pins 105, 106 will enter one of the channels 136 when they do not engage a card during rotation of the sensing wheel.

The provision of the vertically movable plate 135, with its operating connections including the spring 134, provides a yieldable support for the cards at the sensing position so that in the event of a card jam thereat the pressure of the jammed card or cards upon the plate will be sufficient to force the latter downwardly against the tension of the spring 134, and this downward movement of said plate, however slight it may be, will tend to minimize the possibility of damage to the sens-

ing pins 105, 106 by the jammed cards and also reduce the magnitude of the jam by providing additional space between the sensing wheel and the plate through which some of the cards may pass before the machine is stopped.

What is claimed is:

1. In a sorter, a sensing means, a movable card supporting plate in cooperative relation with said means during a sensing operation, means to yieldably maintain said supporting plate in cooperation with said sensing means, means to effect columnar adjustments of said sensing means, and means to move said plate out of cooperative relation with said sensing means during adjustments of the latter.

2. In a sorter, a sensing means including pins, a movable card supporting plate in cooperative relation with said means during a sensing operation and provided with channels for receiving said pins when they are in sensing position, means to yieldably maintain said supporting plate in cooperation with said sensing means, means to effect columnar adjustments of said sensing means, and means controlled by said adjusting means for moving said plate out of cooperative relation with said sensing pins.

3. In a sorter, a rotatable sensing means for sensing cards during transitory movement, a movable card supporting plate mounted below said sensing means, in cooperative relation therewith during a sensing operation, means to yieldably maintain said supporting plate in cooperation with said sensing means, means to effect columnar adjustments of said sensing means, and means controlled by said adjusting means for moving said plate out of cooperative relation with said sensing means.

4. In a sorter, a rotatable sensing device having movements only around and longitudinally of its axis of rotation, a card supporting member movable into and out of cooperative relation with said sensing device, means to yieldably maintain said supporting member in cooperation with said sensing device, means to move said sensing device longitudinally, and means controlled by the operation of said moving means and acting in opposition to the first named means for moving said supporting member out of cooperative relation with said sensing device during said longitudinal movement.

5. In a sorter, a rotatable sensing wheel including sensing pins normally extending in sensing position beyond the periphery of said wheel, a card supporting member having movements into and out of cooperative relation with said pins and provided with channels for receiving the pins when the same are extended and the wheel is rotated, means to yieldably maintain said supporting plate in cooperation with said sensing means, means to adjust said wheel columnwise of a card, and means controlled by the last named means to move said supporting member out of cooperative relation with said pins so that the latter will not extend into said channels.

6. In a sorter, a rotatable sensing wheel including sensing pins normally extending in sensing position beyond the periphery of said wheel, a card supporting member having movements into and out of cooperative relation with said pins and provided with channels for receiving the pins when the same are extended and the wheel is rotated, an operating element for said wheel having means engageable on opposite sides thereof to move said wheel axially when said element is operated, a feed screw for operating said ele-

ment, and connections between said feed screw and card supporting member for moving the latter out of cooperative relation with said pins when said screw is turned.

7. In a sorter, a sensing means, a movable card supporting member normally in association with said sensing means for the passage of cards therebetween while being sensed, and means to yieldably maintain said supporting member in its normal position.

8. In a sorter, a sensing means, a movable card supporting member normally in cooperative position relative to said sensing means and movable out of said position under excessive pressure by cards thereon, and means to maintain said supporting member in its normal position except when excessive pressure is applied to the same by said cards.

9. In a sorter, a sensing means, a card supporting member movable into and out of cooperative relation with said sensing means, a rock-

ing shaft, connections between said shaft and supporting member for moving the latter when said shaft is rocked, an arm movable with said shaft, and a spring connected to said arm and acting through said shaft and connections to normally maintain said supporting member in cooperative relation with said sensing means and yieldable to excessive pressure of cards against said supporting member to permit the latter to move out of cooperative position relative to said sensing means.
